FIGHTER CRAFT

Antoine Gazda, New York, N. Y.

Application November 19, 1941, Serial No. 419,795

5 Claims. (Cl. 114—66.5)

This invention relates to a floating fighter craft which is designed to carry out the same functions upon water that a fighter plane carries out in the air.

It is an object of the invention to provide a construction capable of fighting off floating targets and at the same time capable of defending against air attack.

A further object of the invention is to design a speedy and highly manoeuvrable small craft which may be armed with cannons, machine guns, torpedoes or depth charges, etc. Also, in order to defend against air attack the fighter craft is preferably also armed with antiaircraft guns.

An object of the invention is to provide a construction which will present only the smallest target when attacked, while at the same time carrying high offensive armament.

A still further object of the invention is to construct a fighter craft which has a minimum water and air resistance and which is driven by means of air propellers of either the pusher or puller type. It is, therefore, superior to the vessels driven by means of a water propeller and the invention utilizes considerably less engine power than craft in which a water propeller is used.

With the above and other objects in view which will become apparent from the detailed description below, the invention is shown in the drawings, in which

Figure 1 is a side elevational view of a puller type of craft.

Figure 2 is a plan view of the form of the invention shown in Fig. 1.

Figure 3 is a plan view of a modified form of construction showing the invention applied to a bi-motored craft.

Figure 4 is a side elevational view of the form of the invention shown in Fig. 3, and

Figure 5 is a front elevational view of the craft shown in Figure 3.

Referring to the drawings, similar reference characters are used in the various views to indicate like parts.

In the form of the invention shown in Figs. 1 and 2, the invention is shown as applied to a puller type of craft. It is understood, however, that the invention is just as applicable to the pusher type of craft.

The fuselage is shown at 5 and the propeller at 6. Extending laterally on both sides from the fuselage 5 and secured to the fuselage by any desired means are the elements 7 which may be

termed auxiliary wings. These auxiliary wings 7 are fitted near the center of gravity of the entire craft.

Extending downwardly and secured to the wing 7 at approximately the ends furthest removed from the fuselage are the struts 8 which at their lower ends are secured by any desired means to the floats or boat hulls 9.

A transverse brace 10 is positioned so as to brace the lower end of the leading strut 8 against longitudinal strains.

Also secured to the outer ends of the wings 7 are the longitudinally extending frame members 11 and a strut 12 interconnects the adjacent frame member with the rear of the float 9. The frame members 11 are interconnected at their rearward ends by an adjustable horizontal stabilizer 14 and pivotally connected to the stabilizer 14 is a horizontal controllable elevator 15 which is under the control of the crew.

Also mounted upon the frame members 11 are the vertical stabilizers 16 to which are pivotally secured the rudders 17 under the control of the crew. The floats 9 are also equipped with rudders 18.

During slow speeds the craft will generally be controlled almost exclusively by the rudders 18 in the water, while under higher speeds, the craft will be mainly controlled by the rudders 17. The controls for the rudders are established so that the rudders 17 or the rudders 18 may be operated independently of one another or they may be operated in combination. This permits a high manoeuvrability of the craft.

The floats 9 are also provided with steps 19 as described in my companion application, Serial No. 334,446, filed May 10, 1940, and they are preferably of the nozzle type.

Mounted upon the fuselage is an antiaircraft gun 20 and a cannon 21. Additional cannon and machine guns may be located in the wings 7. Suspended below the fuselage 5 is a torpedo 22. In place of the torpedo, depth charges may be carried or they may be carried in addition to the torpedo. It is obvious that the particular armament used may be varied as desired.

The auxiliary wings 7 are of sufficient size so as to increase the lift of the craft sufficiently so as to reduce the water and air resistance and thereby increase the speed of the craft.

In Figures 3, 4 and 5, the invention is shown as applied to a bi-motored craft. In this modification, floats or hulls are shown at 23, the auxiliary wings at 24 and at the ends of the wings the nacelles 25 are mounted for the engines driving

the puller propellers 26. In this modification, struts 27 extend between the nacelles and the floats 23. The fuselage 28 extends sufficiently to the rear so that the horizontal stabilizers 29 are directly attached to the rear of the fuselage. The horizontal controllable elevators 30 are pivotally connected to the stabilizers 29. At the ends of the horizontal stabilizers 29, the vertical stabilizers 31 are mounted and pivotally secured to these stabilizers are the rudders 32.

The floats 23 are also provided with rudders 33.

In this modification, also, the guns, cannon and torpedo mountings are the same as in the previous construction. It is, of course, obvious that when cannon or machine guns are mounted in the wings 1 or 24 that the fire thereof must be properly correlated with the propellers. Of course, when the pusher type of construction is used, there will be no necessity for correlating the firing of these guns with the propellers. In the modification shown in Figures 3, 4 and 5, braces 34 interconnect the floats and the fuselage.

The high speed of the craft described above is due to the construction outlined which permits a minimum water and air resistance. The step construction provided upon the floats, also, aids in decreasing both the water and air resistance.

In both modifications disclosed above, the control of the rudders as used in the air and the water may be individual or conjunctive.

The auxiliary wings 1 and 24 are sufficient to give a lift to the craft but are not sufficient to take the craft into the air.

I claim:

1. A fighter craft comprising a fuselage, a power plant mounted in said fuselage, a propeller driven by said power plant, an auxiliary wing secured to each side of said fuselage at approximately the center of gravity of the craft, a float attached to the outer end of each of said auxiliary wings, longitudinally extending frame members also secured to the outer ends of said wings, and lateral and horizontal control elements mounted upon said frame members.

2. A fighter craft comprising a fuselage; means for supporting said fuselage consisting of an auxiliary wing attached to each side of the fuselage at approximately the center of gravity of the craft, float securing means dependingly attached to each said auxiliary wing at approximately the outer edge thereof, a float attached to each said securing means, and brace means extending intermediate said floats and fuselage; and at least one horizontal stabilizer.

3. A fighter craft comprising a fuselage; means for supporting said fuselage consisting of an auxiliary wing attached to each side of the fuselage at approximately the center of gravity of the craft, float securing means dependingly attached to each said auxiliary wing at approximately the outer edge thereof, a float attached to each said securing means, and brace means extending intermediate said floats and fuselage; and at least one fixed horizontal stabilizer.

4. A fighter craft comprising a fuselage; means for supporting said fuselage consisting of an auxiliary wing attached to each side of the fuselage at approximately the center of gravity of the craft, float securing means dependingly attached to each said auxiliary wing at approximately the outer edge thereof, a float attached to each said securing means, and brace means extending intermediate said floats and fuselage; and at least one adjustable horizontal stabilizer.

5. A fighter craft comprising a fuselage; means for supporting said fuselage consisting of an auxiliary wing attached to each side of the fuselage at approximately the center of gravity of the craft, float securing means dependingly attached to each said auxiliary wing at approximately the outer edge thereof, a float attached to each said securing means, and brace means extending intermediate said floats and fuselage; at least one adjustable horizontal stabilizer, and at least one controllable horizontal elevator connected with said stabilizer.

ANTOINE GAZDA.
